UNITED STATES PATENT OFFICE

ORVAL C. WINTERS, OF YOUNGSTOWN, OHIO

CRUSHER

Application filed February 20, 1930. Serial No. 429,986.

This invention relates to crushers and has for an object to provide a crusher having great capacity due to the angle of pitch of the sides of the oscillatory crusher head and the speed of the shaft in the novel eccentric block which moves the crusher head. 5

A further object of the invention is to provide a crusher in which the amount of material fed to the crusher is equalized on each side of the crusher by means of a novel hopper having a central plate upon which the material to be crushed is delivered and from thence rolls off onto novel side plates and from thence gravitates between the sides of the crusher head and anvils. 15

A further object of the invention is to provide a crusher in which the spaces between the crusher head and the anvils on opposite sides of the head may be regulated so that the crusher may deliver two different sizes of crushed material at the same time. 20

A further object of the invention is to provide a crusher in which the anvils are yieldably held at the ends remote from their pivots by means of strong springs which permit of the anvils passing out tramp iron and like non-crushable material without breakage to the crusher. 25

A further object of the invention is to provide a crusher in which the working faces of the anvils and the crusher head are lined with manganese steel or other wear resisting material to promote the long life of the crusher. 30

A still further object of the invention is to provide a crusher in which the crusher head is oscillated back and forth on its shaft and strikes and crushes material between the head and novel anvils, the latter being adjustably mounted so that the spaces between the anvils and the head may be enlarged or decreased as desired to crush various sizes of material. 35

A still further object of the invention is to provide a crusher having great capacity combined with low cost of manufacture and low cost of operation. 40

With the above and other objects in view the invention consists in certain novel details of construction and combinations of 45

parts hereinafter fully described and claimed, it being understood that various modifications may be resorted to within the scope of the appended claims without departing from the spirit or sacrificing any of the 55 advantages of the invention.

In the accompanying drawings forming part of this specification,

Figure 1 is a longitudinal sectional view through the crusher taken on the line 1—1 60 Figure 3,

Figure 2 is a plan view of the crusher with the hopper removed,

Figure 3 is a cross-sectional view of the crusher taken on the line 3—3 Figure 1, and 65

Figure 4 is a fragmentary sectional view taken on the line 4—4 Figure 1, showing the lining plates of the crusher head.

Referring now to the drawings in which like characters of reference designate similar parts in the various views, the crusher is shown to comprise a casing preferably formed in three sections, the upper section comprising a hopper 10, the central section comprising side walls 11, and a base section 12. All of these sections are preferably detachable from each other and are secured together by bolts 13 passed through suitable flanges 14 carried by the sections at their 70 meeting edges. 80

A pair of anvils 15 are pivoted to the side walls 11 of the casing below the hopper, each anvil being provided with spaced ears 16 on the outer face which receive a pivot shaft 17, 85 the ends of which are journaled in suitable bearings 18 formed in the side walls 11. It will be noted that there are a plurality of these bearings 18 so that the pivot shaft may be removed from one set of bearings and inserted in another set in order to vary the width of the spaces between both anvils and the crusher head as will be hereinafter described in detail. 90

The anvils 15 slope downwardly and outwardly below the hopper 10 and diverge from their pivoted upper ends towards the base section 12 as best shown in Figure 1. The anvils are furthermore yieldably secured at the lower ends to the side walls 11 of the 100

casing by mechanisms which will now be described.

Each anvil is provided with a pair of spaced cross bars 18 and 19, the cross bar 18 being preferably bolted to the anvil as shown at 20. A pair of bolts 21 are secured in lugs 22 carried by the lower section 12 and pass through openings formed in both cross bars 18 and 19. Strong helical springs 23 are disposed on the bolts between the cross bars 18 and 19. The bolts thus secure the anvils to the casing and also perform the function of guides upon which the lower cross bar 18 may move outwardly against the pressure of the springs 23 to permit the escape of non-crushable material without injury to the crusher.

Supplemental guides 24 as best shown in Figure 2 are secured to the lower cross bar 18 of each anvil and are slidably received in openings formed in the upper cross bar, there being strong helical springs 25 disposed on these guides between the cross bars.

A wedge or liner 26 is disposed between the lower cross bar 18 of each anvil and the outer face of the anvil and held in place by the above described bolts 20. There are preferably a plurality of these liners of different thicknesses so that when the pivots of the anvils are adjusted outwardly or inwardly a liner of corresponding thickness may be substituted for the purpose of varying the width of the space between each anvil and the crusher head.

The crusher head 27 is preferably formed of a casting of triangular contour, the sides of which are rather steeply pitched and diverge downwardly and outwardly from the hopper towards the base section 12 of the casing. The bottom face of the head is curved upwardly as shown at 28 for a purpose which will presently appear. The head is pivoted near the upper end to the side walls 11 of the casing by means of a pivot shaft 29 passing through the head and through suitable bearings 30 formed in the side walls 11. The crusher head is oscillated back and forth on the pivot shaft 29 and coacts with the anvils 15 in crushing material gravitating into the spaces between the anvils and crusher head from the hopper 10.

For oscillating the crusher head a shaft 31 is journaled in suitable bearings 32 in the base section 12 and passes therethrough, the shaft being equipped at one end with a belt pulley 33 and at the opposite end with a fly wheel 34. Disposed centrally on the shaft is a cam sleeve 35. The cam sleeve is rigidly secured to the shaft 31 in any preferred manner.

A block 36 is provided with an eccentric opening 37 to receive the cam 35. The block is connected to the opposite sides of the crusher head by means of links 38, these links being arranged on opposite sides of the shaft 31 and one being arranged above the

shaft and the other being arranged below the shaft. By this arrangement of the links when the block 36 is oscillated by the cam 35, the links will exert an alternate pull upon the crusher head to oscillate the same.

The links 38 preferably are passed in between hinge ears 39 on the eccentric block and also between hinge ears 40 formed on the crusher head. Pivot pins 41 and 42 are passed through the hinge ears on the eccentric block and on the crusher head respectively to pivotally secure the links to these parts.

Lubricating cups 43 are arranged to lubricate the pivot pins of the links and the shaft 31 and are fed through flexible tubes 44 passed through the sides of the sections 11 and 12 of the casing. The pivot pins are also preferably provided with bushings 45. Furthermore, it is intended in practice to protect the pivots of the links 38 with leather boots which may be of any desired type.

It will be here noted that the upwardly curved lower wall 28 of the crusher head houses the cam shaft 31 and eccentric block 36 so that these parts are protected from injury.

By referring now to Figure 1 it will be seen that a plurality of plates are arranged in staggered relationship in the hopper 10, there being a central plate 46 disposed above the crusher head 27, and also there being side plates 47 disposed below the plate 46 and extending above the anvils 15. Material dumped into the hopper will be delivered onto the central plate 46 and from thence rolls off onto the side plates 47 and from thence gravitates into the spaces between the anvils 15 and working faces of the crusher head 27. Thus, two equal streams of material will gravitate between the crusher head and the anvils and will be crushed at the same time.

Obviously, by moving one or both of the anvils 15 outwardly by adjusting the pivot shafts 17 thereof in selected bearings 18 the spaces between the crusher head and the anvils will be widened to crush material to other sizes than ordinarily. The proper width liner 26 must be used when any adjustment of the pivot shaft 17 is made in order that the working faces of the anvil and confronting working face of the crusher head will remain nearly parallel. However, for a slight adjustment, liner 26 may be changed independent of the pivot shafts 17.

It will be here noted that by adjusting one of the anvils to maintain a narrow space between it and the confronting face of the crusher head while the opposite anvil is disposed to produce a wide space between it and the confronting face of the crusher head, two different sizes of crushed material may be simultaneously delivered.

Arranged below the base section 12 of the crusher there are two chutes 48 which re-

ceive the gravitating crushed material from the anvils.

In order to promote long life of the parts both anvils are preferably faced with plates 49 of manganese steel or other wear-resisting material backed with zinc, and likewise the working faces of the crusher head are faced with similar plates 50. Furthermore, the top of the crusher head is faced with a plate 51 of similar wear-resisting material. The inner faces of the casing sides 11 are also faced with similar plates 52. All of the wear resisting plates are preferably removably secured in position by screws 53. Furthermore, the facing plates of the crusher head, anvils, and casing sides are turned over the end faces of the respective parts to provide flanges 54 which are secured in place by screws 55.

It will now be apparent that should tramp iron or other non-crushable material fall into the crusher between the crusher head and anvils the springs 23 and 25 will yield under impact of the non-crushable material and permit the same to pass from between the crusher head and anvils without danger of injury to any of these parts. From the above description it will be seen by virtue of the steep pitch of the working faces of the crusher head that when the cam shaft 31 is driven at comparatively high speed a great quantity of material may be crushed in minimum time. This great capacity of the crusher is produced without danger of breakage to the parts due to the novel construction and arrangement thereof as above described. It will be further noted that the crusher is formed of a few simple, rugged and durable parts which are not expensive to manufacture and will not easily get out of order.

It is thought that from the above description the construction and operation of my invention will be easily understood.

Having thus described the invention, I claim:

1. A crusher comprising a casing, anvils therein, a shaft, a cam on the shaft, a crusher head between and coacting with the anvils, an eccentric block operated by the cam, and a pair of links pivotally connected to the block and pivotally connected to the head and adapted to oscillate said head by exerting an alternate pull upon the head.

2. A crusher comprising a casing, diverging anvils in said casing, a crusher head having diverging sides coacting with said anvils, a cam shaft, an oscillatory block operated by the cam shaft, and links pivotally connected to the block above and below the cam shaft and pivotally connected to opposite sides of said head for oscillating said head.

3. A crusher comprising a casing, diverging anvils in said casing, a head pivoted to said casing and having diverging sides coacting with the anvils, a cam shaft, an eccentric block operated by the cam shaft, links piv-

oted to the block and to opposite sides of the head for oscillating the head, and a hopper above the casing adapted to deliver separate streams of material to be crushed into the spaces between the opposite sides of the head 70 and the anvils.

4. A crusher comprising a casing, diverging anvils pivoted at the upper ends to said casing, a head between the anvils pivoted to said casing and having diverging sides confronting said diverging anvils, a cam shaft, an eccentric block operated by the cam shaft, a link connecting the block to the head for oscillating said head to crush material against said anvils, and means for yieldably 80 securing the lower ends of said anvils to said casing to permit the passage of non-crushable material without breakage to the crusher.

5. A crusher comprising a casing, a crusher head pivoted in the casing, anvils pivoted at the upper ends in the casing and disposed on opposite sides of the head, a cam shaft, an eccentric block operated by the cam shaft, a link connecting the block to the head for oscillating the head, means for adjustably securing the pivots of said anvils to said casing, means for securing the lower ends of said anvils to said casing, and liner strips carried by the last named means and cooperating with the first named means to vary 95 the width of the spaces between said head and said anvils whereby various sizes of materials may be crushed.

6. A crusher comprising a casing, a hopper above the casing, staggered plates within the hopper permitting the passage of material into the casing in spaced streams, a crusher head in the casing below said staggered plates, a cam shaft, an eccentric block operated by the cam shaft, a link connecting the block to the head for oscillating the head, anvils secured to said casing outside of said head, the confronting faces of said head and said anvils simultaneously crushing the material of said spaced streams, and means 110 for adjustably mounting either of said anvils on the casing whereby the material of each stream may be crushed to a different size than that of the other stream.

7. A crusher comprising a casing, anvils therein pivoted at the upper ends to the casing, means yieldably securing the lower ends of the anvils to the casing, said anvils sloping downwardly and outwardly within the casing, a substantially triangular crusher head between the anvils pivoted at the upper end to the casing and having sloping sides coacting with said anvils and having an upwardly curved bottom, a cam shaft, an eccentric block on the cam shaft housed within the curved bottom of said head, and links pivotally connected to said block and to said head on opposite sides of said cam shaft for transmitting oscillatory movement of said block to said head.

8. A crusher comprising a casing, anvils therein, a crusher head between the anvils, and means for oscillating the head to crush material against the anvils, said means comprising a cam shaft, an eccentric block on said cam shaft, and a pair of links pivotally connected to said block and to said head on opposite sides of said cam shaft, one of said links being disposed below the cam shaft and the other being disposed above the cam shaft whereby the links exert an alternate pull upon the head.

9. A crusher comprising a casing, anvils in the casing, a crusher head pivoted to said casing between said anvils, wear-resisting plates disposed on the working faces of said anvils and said crusher head, a cam shaft, an eccentric block operated by said cam shaft, links pivotally connected to said block and pivotally connected to said crusher head for oscillating the head, and spaced chutes below the head adapted to receive the separate streams of material crushed between the head and the anvils.

25 In testimony whereof I affix my signature.
ORVAL C. WINTERS. [L.S.]
